UNITED STATES PATENT OFFICE.

WINFIELD SCOTT MOORE, OF INDIANAPOLIS, INDIANA.

MOUTHPIECE FOR TELEPHONE-TRANSMITTERS.

SPECIFICATION forming part of Letters Patent No. 665,251, dated January 1, 1901.

Application filed May 21, 1900. Serial No. 17,447. (No model.)

To all whom it may concern:

Be it known that I, WINFIELD SCOTT MOORE, a citizen of the United States, residing at Indianapolis, in the county of Marion and State 5 of Indiana, have invented certain new and useful Improvements in Mouthpieces for Telephone-Transmitters, of which the following is a specification.

The object of my said invention is to provide 10 a mouthpiece to be used with telephone-transmitters, by means of which comparative privacy of conversation may be secured when other persons are present, and also whereby echoing and reverberating effects may be precluded and at the same time the ordinary 15 use of the transmitter be not interfered with.

Said invention will be first fully described, and the novel features thereof then pointed out in the claims.

Referring to the accompanying drawings, which are made a part hereof, and on which similar reference characters indicate similar parts, Figure 1 is a side elevation of the mouthpiece of a transmitter and a fragment 25 of the casing carrying the same, my improved attachment being connected to said mouthpiece, a second position being shown by dotted lines; Fig. 2, a front elevation of the same, and Fig. 3 a central vertical section on 30 the dotted line 3-3 in Fig. 2.

My attachment is composed of a mouthpiece proper, 1, which is of a shape to substantially inclose the mouth and nostrils of the speaker while using the same, a preferably flexible tube 2 of a convenient length, and a T-shaped hollow piece 3, extending across the ordinary mouthpiece of the transmitter, to one arm of which the flexible tube is connected, the other arm being open, as 35 shown, while the stem of the T extends at right angles with the arms to a point near the diaphragm of the transmitter. A bridge-bar 4, suitably connected to the T-shaped piece 3, forms the means of attaching my device to the transmitter. Said bridge-bar is 40 comparatively narrow, so that the major portion of the transmitter-mouth is open and may be used in the ordinary manner, and when so used my attachment hangs idly and 45 neither interferes with nor affects the operation in any manner. The bridge-bar 4 is

attached in any convenient manner, being shown with hooks *h* formed on one end and a clamp-screw *s* carried by the other, which operate in a manner which will be readily 55 understood.

I have discovered by considerable experiment that when a tubular mouthpiece is used as an attachment to the regular mouthpiece of a transmitter, if it is so constructed as to 60 convey the vibrations of the voice with full force against the diaphragm, much reverberation ensues, causing the instrument to operate badly and detracting much from its efficiency. One principal object of my invention has been to remedy this difficulty, and this I have done by carrying the transmitting-tube straight across an ordinary transmitter-mouth, leaving its opposite end 65 open, while the sound is conveyed to the diaphragm by a branch running at right angles with said tube this, in the construction shown being the stem of the T.

Another advantage arising from the open end is that foul air or breath is not confined 70 in the tube, and the use of such an attachment is thus rendered much more pleasant and under better sanitary conditions.

My device, as shown, merely crosses and does not cover the ordinary transmitter. It 75 is therefore entirely practicable to use a telephone provided with my attachment in the ordinary manner, the attachment meantime hanging idle and being without effect, which of course is impossible where the device fills 80 or covers the ordinary transmitter-mouth.

Having thus fully described my said invention, what I claim as new, and desire to secure by Letters Patent, is—

1. The combination, with a telephone-transmitter, of an extension-mouthpiece attachment comprising a suitable mouthpiece proper, a tube extending therefrom, and a T secured to the ordinary transmitter-mouth, to one arm whereof the tube is connected, the 90 other arm extending across the transmitter and being open, while the stem of the T extends at right angles in toward the transmitter-diaphragm, substantially as shown and described.

2. The combination, with a telephone-transmitter, of an extension-mouthpiece attach-

ment extending across but not covering the transmitter - mouth and having an opening into said transmitter, thus enabling the transmitter to be used in the ordinary manner
5 without removing the attachment, substantially as shown and described.

In witness whereof I have hereunto set my

hand and seal, at Indianapolis, Indiana, this
19th day of May, A. D. 1900.

WINFIELD SCOTT MOORE. [L. S.]
